UNITED STATES PATENT OFFICE.

EDMONDS J. SUGDEN, OF PITTSBURG, PENNSYLVANIA.

WHIFFLETREE OR NECK-YOKE IRON.

SPECIFICATION forming part of Letters Patent No. 398,553, dated February 26, 1889.

Application filed June 19, 1888. Serial No. 277,534. (No model.)

To all whom it may concern:

Be it known that I, EDMONDS J. SUGDEN, of Pittsburgh, in the county of Allegheny and State of Pennsylvania, have invented a new 5 and useful Improvement in Singletrees, Doubletrees, and Neck-Yokes; and I do hereby declare the following to be a full, clear, and exact description thereof.

My invention relates to an improvement in 10 singletrees, doubletrees, or neck-yokes for vehicles, in all of which articles the strain is upon the ends, while the point of resistance where the bar is attached to the vehicle is at or near the middle. Heretofore these articles 15 have been made of wood, and while attempts have been made to construct them of metal the metal articles have not been desirable, because they are not of sufficient strength and because they are not of proper 20 shape to afford to the bar its necessary property of elasticity. In articles of this kind it is not only necessary that they shall be of sufficient rigidity to stand the strain to which they are subjected, but that they should be 25 sufficiently elastic to yield somewhat when the strain is very great, and when the strain is relieved they should spring back into their original shape.

It is the object of my invention to produce 30 articles of this kind which shall possess all these desirable features, combining the greatest strength with lightness of weight and elasticity. To this end I make them of steel bars provided with longitudinal flanges or ribs, 35 these bars being formed, preferably, by rolling, so that the flanges shall taper from a point or points at or near the middle toward the ends. The flanges give the bar great strength without undue increase in weight, 40 and the tapering form hereinafter described, together with the flanges, imparts the desired elasticity. In order that the strength of the bar shall not be diminished, I prefer to reduce the flanges of the bar in tapering form from 45 the middle toward the ends, so as to diminish their height or radial dimension without materially diminishing their thickness; and I prefer also not to reduce the center or core of the bar except near the ends, where it is preferably reduced to properly form the eyes of 50 the bar; but otherwise I prefer to have the core of equal thickness throughout the bar,

the flanges only being reduced. After the article has been formed it is preferably hardened and tempered in the usual manner of 55 hardening and tempering steel for springs. The purpose of this is to increase the elasticity.

Many forms of steel bar may be used for the purpose of my invention, and I have 60 shown a number of them in the drawings, but do not desire to limit myself strictly thereto.

In the accompanying drawings, Figure 1 is a plan view of one of my improved singletrees. Fig. 2 is a vertical cross-section on the 65 line $x-x$ of Fig. 1. Fig. 3 is a section on the line $y-y$ of Fig. 1. Figs. 4, 5, and 6 are cross-sectional views of modified forms of bar embodying my invention. Fig. 7 is a longitudinal section on the lines $z-z$ of Figs. 2 and 3. 70

Like symbols of reference indicate like parts in each.

In the manufacture of these articles I first take a bar of steel of the character of which I have described and shown, and, having cut 75 it into suitable lengths, I roll it or otherwise form it into the shape shown in Fig. 1, so that the flanges or ribs shall taper in one only of their cross-sectional dimensions, preferably in height and not in thickness, though they 80 may be reduced in thickness but not in height with good results. This taper extends from a point or points at or near the middle of the bar 2 toward the ends, the core or center of the bar being preferably unreduced, except at 85 the ends. The ends of the bar are partially bent to form eyes 3, for the purpose of holding the hooks by which the chains are fastened to the bar. The article is then hardened and tempered in the manner usually practiced 90 in hardening and tempering steel springs. The clevis 4 is then shrunk on at the middle of the bar, and, the extreme ends of the bar having been heated, the partially-formed eyes 3 are closed around the usual chain hooks or rings, 5 95 as shown in Fig. 1. The article is then complete and ready for use. That part of the clevis which is shrunk or compressed on the bar is a somewhat broad band of iron, and the shrinking of it on at this place, where the greatest strain comes in use, strengthens the bar 100 and greatly increases its efficiency.

The advantages of my improvement have been demonstrated by practical use and ex-

perience, and I have found that articles made as I have described are much lighter than wooden articles of the same strength, are much neater, more durable, and by reason of their elasticity they relieve the horses from the great strain of starting with heavy loads without the use of separate tug-springs or other appliances.

By reference to the figures of the drawings 10 it will be seen that the metal bars which I show are all substantially the same, in that they are all radially and longitudinally flanged or ribbed. In making them into the desired tapering form all of the flanges may be tapered, as shown in Fig. 1, or only one of the flanges may be tapered; or, if desired, two or 15 any number of the flanges less than the whole may be tapered.

I am aware that iron of the same shape in 20 cross-section as that I have shown and described has been mentioned in a prior patent, No. 243,730, as being desirable for use in the construction of vehicle-axles for the purpose of making them strong and light. My invention, however, is altogether different from this, because the metal bar which I use is not the same in form, being tapered from at or near the middle toward the ends, while the vehicle-axle is of constant thickness, except 25 at the extreme ends, where it fits within the spindles. Besides this, the conditions of use to which the articles are put are altogether different, the axle being designed to be of the greatest possible rigidity and strength, while 30 I form my bars to secure articles possessing the greatest possible elasticity consistent with the degree of strength requisite for the purpose for which the articles are to be used.

I am also aware that it has been proposed 40 to make vehicle-springs of longitudinally and radially flanged steel bars, the whole of the bar, both flanges and core, being reduced in thickness and width from the middle toward the ends. This, however, would unduly 45 weaken the bar, and I do not claim the same broadly, even as applied to singletrees, &c.; but my invention consists, broadly speaking, in a vehicle-iron of the nature described, which is tapered from at or near the middle

toward the ends in any number of respects 50 less than the whole, for the purpose of giving the necessary elasticity without impairing the strength—that is to say, the core may be tapered, leaving the flanges tapered in only one dimension, or the flanges may be tapered in 55 one dimension and not in the other, whether the core be tapered or not.

I do not limit my invention to its application to any particular style or shape of singletrees, doubletrees, or neck-yokes, except as 60 stated in the claims. Any desired pattern or style may be made according to my invention, and any suitable fittings may be applied to them.

I claim—

1. A vehicle-iron of the nature described consisting of a radially and longitudinally webbed or flanged steel bar, the flanges of which are reduced in height but not in thickness from at or near the middle of the bar toward its ends, substantially as and for the purposes described.

2. A vehicle-iron of the nature described consisting of a radially and longitudinally webbed or flanged steel bar, the flanges of which are gradually reduced in one only of the cross-sectional dimensions from at or near the middle toward the ends, substantially as and for the purposes described.

3. A vehicle-iron of the nature described consisting of a radially and longitudinally webbed or flanged steel bar, the flanges of which are reduced, the core of the bar being of substantially the same dimension for a considerable portion of its length, substantially as and for the purposes described.

4. A vehicle-iron of the nature described consisting of a radially and longitudinally webbed or flanged steel bar having a clevis-band set thereon at the middle, substantially as and for the purposes described.

In testimony whereof I have hereunto set my hand this 1st day of June, A. D. 1888.

EDMONDS J. SUGDEN.
